UNITED STATES PATENT OFFICE

PHILIP J. G. VETTER, OF BROOKLYN, NEW YORK.

CLOTHESLINE-BRACKET.

1,394,239.

Specification of Letters Patent.

Patented Oct. 18, 1921.

Application filed December 1, 1919. Serial No. 341,740.

To all whom it may concern:

Be it known that I, PHILIP J. G. VETTER, a citizen of the United States of America, residing at 2345 Putnam avenue, Brooklyn, 5 New York, in the county of Queens and State of New York, have invented certain new and useful Improvements in Clothesline-Brackets, of which the following is a specification.

10 This invention relates to clothes line supports and has particular reference to that class of such devices as are intended for use in apartment houses or the like where the clothes to be dried are hung from windows 15 along lines leading to distant posts or other supports.

Among the objects of the invention is to provide a means of a cheap, simple and reliable nature adapting the operator to hang 20 the clothes upon the line without the necessity of reaching out of the window for this purpose.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a side elevation of a clothes line apparatus showing the position thereof with respect to the building while the clothes are being put upon the line and projected outwardly through the window.

Fig. 2 is a sectional view through the 40 center of the attaching bracket.

Fig. 3 is a side elevation on an enlarged scale showing the movable arm folded downwardly so that the window may be closed.

Fig. 4 is a detailed perspective view of the 45 combined double hook and pivot pin on which the bar and clothes line are supported.

Fig. 5 is a detail of one end of the pivoted bar.

In Figs. 1 and 2, the bracket or other part 50 adapted to be attached to the window frame 1 is shown as in the form of a metal plate 2 having holes 3 therein for attaching it by screws 4 or other fastening means to the window frame 1. Said plate is provided 55 with a slot 5 or other guideway adapted to receive and guide a pin 6 or the like on the

pivoted bar 7. Preferably said slot is inclined to the vertical and possesses a straight or regular portion 8 and a recess at either end, the upper recess 9 being preferably substantially vertical and the lower recess 10 substantially horizontal.

The clothes line supporting bar 7 is pivoted on said bracket adjacent its inner end by any suitable means such as a pin 11 secured in 60 said bracket working in a slot 12 in said bar. Said slot is elongated so that the bar may have a limited slidable movement as well as rotation. Said pin 11 may also have one or more hooks 13 and 14 thereon for guiding 70 the clothes line 15. The outer end of the bar is also provided with a hook 16 to which a pulley 17 may be attached. It will be understood that the double line 15 runs around a similar pulley (not shown) on a pole in 75 the yard for instance. The slot 5 is preferably duplicated by a reversely inclined portion 8' in the lower portion of plate 2, which is provided with the vertical recess 9'. By this simple means, not only may the bar 7 80 be folded either upwardly or downwardly when it is desired to close the window to suit the preference of the operator, but the important advantage is gained that the same bracket may be attached to either side of the 85 window frame, thereby lessening manufacturing costs.

From the foregoing description the general use of my invention will be readily apparent. If desired to hang the wash on 90 the line the bar 7 is turned to a substantially horizontal position as shown in Fig. 1 and pushed to the right so that the pin 11 engages in the niche 10. After the lower portion of line 15 is disengaged from hook 13 95 (see dotted line 15' in Fig. 1) each piece is then pinned to the line and the line hauled outwardly in the usual manner. After the operation is completed the line is replaced in hook 13 and the bar is drawn to the left, 100 disengaging the pin from the niche as aforesaid, and turned either downwardly or upwardly according to the desire of the operator and when it is in substantially vertical position pushed upwardly or downwardly as 105 the case may be to engage the pin in one of the vertical recesses or niches 9 or 9'. By this movement the tautness of the line is maintained without undue stretching and at the same time the tension on the line 110 serves to maintain the rod in its locked position as shown in Fig. 3 by pulling upwardly

on the rod and holding the pin in the niche. It will also be noted that in Fig. 1 the tension of the line also acts to maintain the pin in niche 10 and the rod in the horizontal position without the use of springs or other means.

In accordance with the provisions of the patent statutes, I have herein described the principle of operation of my invention, together with the apparatus, which I now consider to represent the best embodiment thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

25 1. A clothes line support comprising a bracket adapted to be secured to a window frame and having a slot therein, a clothes line supporting bar pivotally and slidably attached to said bracket, a pin on said bar adapted to work in said slot, and means on said bar for guiding a clothes line.

30 2. A clothes line support comprising a bracket adapted to be secured to a window frame and having a slot therein, a clothes line supporting bar pivotally and slidably attached to said bracket, a pin on said bar, said slot having a pair of niches at spaced points thereon adapted to receive the pin and hold the bar in either of two angular positions, and means on said bar for guiding a clothes line.

35 3. A clothes line support comprising a bracket adapted to be secured to a window

frame and having an angularly positioned guideway, vertical and lateral recesses therein, a bar slidably and pivotally mounted on said bracket, and means on said bar engaging in said guideway and adapted to hold the bar either substantially vertical or substantially horizontal when in the proper recess.

4. A clothes line support comprising a bracket adapted to be secured to a window frame and having an angularly positioned guideway, substantially vertical and horizontal recesses therein, a bar slidably and pivotally mounted on said bracket, a guide for the line mounted on said bracket adjacent the pivot of said bar, and means on said bar engaging in said guideway and adapted to hold the bar either substantially vertical or substantially horizontal when in the proper recess, the tension of the line serving to hold said means in the locked position.

5. A clothes line support comprising a bracket adapted to be secured to a window frame and having a slot therein, a clothes line supporting bar pivotally and slidably attached to said bracket, means adjacent the outer extremity of said bar for securing a clothes line, a fixed guide for the line adjacent the pivot of said bar, and a pin on said bar on the opposite side of the pivot from said securing means, said slot being of angular form with the apex of said angle extending in the opposite direction to the bar when in its horizontal position and having a horizontal niche at said apex and a vertical niche at each end of said slot, said niches being adapted to receive the pin and hold the bar in any one of a plurality of angular positions whereby the tension of the line holds the pin in the niches.

In testimony whereof I have affixed my signature.

PHILIP J. G. VETTER.
